OIL BURNING STEAM BOILER

Philias P. Monfils, Worcester, Mass.

Application December 15, 1933, Serial No. 702,572

4 Claims. (Cl. 122—261)

The present invention relates to a steam boiler construction and particularly to an oil or gas-burning boiler arranged to circulate the gases from the burner in such a manner that substantially all of the heat from the gases is utilized in heating the water in the boiler.

In prior devices of this character, the burner nozzle is located beneath the boiler and the hot gases from the nozzle pass substantially vertically through the boiler to the stack. The movement of the gases is so rapid, especially in a burner in which the oil, or oil mixed with air for combustion, is blown into the fire box at a relatively high pressure that only a small portion of the heat in the gases is delivered to the boiler. One of the principal objects of the present invention is accordingly to provide for a circulation of the gases so that practically all of the available heat may be delivered to the boiler before the gases are discharged from said boiler.

In steam boiler constructions for supplying steam at a low pressure as in heating a house, it has frequently been the custom to install an oil or gas burning unit in the fire box of a heater originally designed for the burning of wood, coal, or coke. It will be apparent that such a burner cannot be efficient since a boiler arranged to be heated from a bed of coals cannot be efficiently heated from moving heated gases. Thus, a further object of the present invention is to provide a low pressure steam boiler especially designed for the burning of liquid or gaseous fuels.

Other and further objects and advantages of the invention will appear from the following detailed description taken in connection with the accompanying drawings in which:—

Fig. 1 is a vertical section through a steam boiler embodying the invention, the section being substantially along the line 1—1 of Fig. 2.

Fig. 2 is a horizontal section through the boiler substantially along the line 2—2 of Fig. 1.

Fig. 3 is a horizontal sectional view along the line 3—3 of Fig. 1.

Like reference characters refer to like parts in the different figures.

Referring first to Fig. 1, the boiler construction comprises a substantially cylindrical outer shell 1 having a lining of fire brick or other refractory material 2 and within which is located the boiler proper 3 of a novel construction as will be hereinafter pointed out. Supports 4 (see also Fig. 2), positioned within the shield at the lower end thereof, support the boiler 3 in proper position within the shell. The latter is provided with an opening 5 adjacent the bottom thereof

for the discharge of gases from within said shell after they have circulated around the boiler, the opening 5 being suitably connected to a chimney or stack not shown. The shell 1 is also provided with a second opening 6 adjacent the bottom thereof, forming a manhole to provide access to the inside of the boiler.

According to the invention, the boiler proper comprises a boiler head 7 from which depends a vertical water-leg 8, the latter defining an approximate spiral about a vertical axis, as best shown in Fig. 2, said leg opening into the boiler at the upper end thereof. Centrally of the boiler head 7 and extending downwardly therefrom is positioned an upright 9, Figs. 1 and 2, the lower end of said upright resting on the supports 4. One edge of each of a pair of parallel plates 10 and 11 are secured to said upright on opposite sides thereof, and the plates extend outwardly from said upright in spiral arrangement to form the spiral water-leg. The upper ends of the plates 10 and 11 are secured, as by welding, to the bottom wall 12 of the boiler head 7 which has a spiral opening coextensive with the space between the plates to provide a direct connection between the water-leg and the boiler head. The lower ends of the plates are secured, as by welding, to the opposite sides of a spiral member 13 which acts as a closure for the lower end of the water-leg and which rests on the supports 4, the latter being normally provided with recesses 14 to receive said member and to retain said member in proper spiral configuration. The water-leg has a plurality of successive turns 8^a, 8^b and 8^c which define therebetween a continuous spiral opening through which the burning fuel and hot gases are directed, as will hereinafter appear.

A fire box 15 is provided adjacent the lower portion of the water-leg directly above the supports 4, and an auxiliary boiler head 16 is located directly above said fire box substantially midway of the height of the water-leg. As best shown in Fig. 2, the end 17 of the water coil 8^c of the water-leg below the auxiliary boiler head extends away from the adjacent coil 8^b to form the outer wall of the fire-box. Said wall is spaced from the fire-brick lining 2, as shown, for the purpose which will hereinafter appear. The opposite or inner wall of the fire box is formed by a portion 18 of the coil 8^b of the water-leg, and the bottom wall 19 of the auxiliary boiler head extends between the plates 10 and 11 of the outer coil 8^c and the adjacent coil 8^b respectively to form the top wall of the fire box, said plate 19 being suitably secured to both the plates 10 and 11.

10 and 11 as by welding. The bottom wall of the fire box is formed by a plate 20 resting on the supports 4 and extending between the portions 17 and 18 of the coils 8^c and 8^b of the water-leg. 5 An opening 21 in the shell 1 and the fire-brick lining 2 provides for the injection of the desired combustible mixture of oil or gas and air by any suitable device. Opposite the opening 21, the fire box tapers gradually for directing the hot gases 10 into the spiral space 22 between the coils of the water-leg.

Above the auxiliary boiler head, the end portion 23 of the outer coil 8^c of the water-leg extends in parallel relation to the inner coils as 15 indicated in Fig. 3 and the outer edges of the plates 10 and 11 forming said coil are secured together as indicated at 24. Below the auxiliary boiler head, the outer edges of the plates 10 and 11 are secured to opposite sides of a vertical bar 25 to form a water-tight closure.

The upper wall of the auxiliary boiler head is formed by a plate 26 extending between the lower edge of the outer wall of the portion 23 of the water-leg above the auxiliary boiler head and the 25 upper edge of the outer wall of the portion 17 of the water-leg, said plate 26 being suitably secured to said walls as by welding. A second plate 27 extends between the coils 8^b and 8^c above the auxiliary boiler head to form a part of the top 30 wall thereof and said plate is secured to the lower edges of the inner wall 10 of the portion 23 and to the outer wall 11 of the coil 8^b. A portion 28 of the inner wall 10 of the outer coil 8^c, in alinement with the auxiliary boiler head is 35 turned inwardly between the coils 8^c and 8^b, as indicated by the dot-dash lines of Fig. 2, to form a part of the side wall of the auxiliary boiler head, and the plate or wall 27 extends inwardly to engage the top of the portion 28. The end of 40 the auxiliary boiler head directly above the opening 21 into the fire box is closed by a plate 29 which is secured to the plates 26 and 27 to the plate 19 forming the lower wall of the boiler head, to the inner wall of the portion 17 of the outer coil 8^c and to the outer wall of the coil 8^b, thus forming a water-tight closure for the end 45 of the boiler head. The walls 26 and 27 are suitably held in desired relation to the bottom wall 19 by stay-bolts 30 and the top and bottom walls 50 of the main boiler heads are held by stay-bolts 31.

A pipe 32 is secured to an opening 33 in the top wall of the boiler head 1 for the discharge of steam generated in said boiler. The amount of water in the boiler is indicated by the usual indicating apparatus 34 which is connected by pipes 35 and 36 to the auxiliary boiler head and the main boiler head respectively. A suitable pressure gage 37 is provided and a suitable drain pipe 38 is connected to a portion of the water-leg adjacent the lower end thereof. The boiler is also provided with a water inlet 39 located at the end of the water-leg remote from the drain connection. A portion of the main boiler head extends above the shell 1 and is preferably covered by any suitable heat insulating material 40, the latter also extending over the outside of the shell.

In the operation of the boiler, the liquid or gaseous fuel is injected into the fire box through 70 the opening 21 by any suitable blower not shown, and the pressure existing in the fire box directs the burning gases and the products of combustion into the spiral space 22 defined by the coils of the water-leg. The vertical movement of the 75 gases is restricted so that they remain in the

lower portion of the water-leg during their spiral movement into the center of the spiral. To this end, a series of members 41 of I-beam section are mounted on the supports 4 with the upper ends of said sections located approximately on 5 the level of the auxiliary boiler head and substantially filling the space between the successive coils of the water-leg. As the end of each member 41 abuts the adjacent member, the gases are directed spirally in the space 22 without passing 10 upwardly beyond the upper ends of the I-beams. The gases ultimately reach the center of the spiral which, as shown in the drawings, is open the 15 entire height of the water-leg and the gases are discharged upwardly therein to begin a second spiral movement in the space 22. This movement, as indicated in Fig. 3 however, involves an outward movement of the gases until they reach an annular space provided between the outer coil 8^c of the water-leg and the refractory lining 2. 20 This annular space 42 is closed at the bottom by an arcuate plate 43 except for a space adjacent to the portion 17 of the outer coil 8^c. This opening or space communicates with the opening beneath the boiler and around the supports 4 and 25 the products of combustion discharge from the annular space 42 through said opening into the space around the supports 4 and subsequently through the discharge opening 5. By the movement of the gases and products of combustion 30 spirally around the water-leg substantially all of the heat in the gases is delivered to the boiler. At the same time, by the provision of an auxiliary boiler head directly above the fire box and the placing of portions of the water-leg on opposite 35 sides of the fire box, it is possible to obtain a large amount of heat from the gases where the heat is most intense. The necessity for lining the fire box is thereby eliminated. It may be noted that the gases from the fire box pass spirally 40 around the water-leg to the center thereof where they move upwardly and then move outwardly spirally around the water-leg for discharge. By this construction, a circuitous continuous path is provided for the hot gases and the path is 45 sufficiently long to provide for the removal of a large amount of the heat from the gases before they are discharged through the opening 5. To provide for safe operation of the boiler, fusible plugs 44 may be provided in the plates 10 and 11 50 respectively on opposite sides of the fire box.

I claim:

1. In a boiler construction adapted for the combustion of liquid or gaseous fuels, a boiler head, a water-leg depending therefrom and forming a continuous spiral about a substantially vertical axis, said water-leg defining a continuous spiral path through which the products of combustion are directed and a horizontal dividing member between the top and bottom of said water-leg for preventing vertical movement of the products of combustion in said spiral path, the inner end of said dividing member being spaced from the center of the spiral to permit vertical movement of the products of combustion at the 60 center of the spiral.

2. In a boiler construction adapted for the combustion of liquid or gaseous fuels, a boiler head, a water-leg depending therefrom and forming a continuous spiral, said water-leg defining a continuous spiral path through which the products of combustion are directed, and a dividing member between the opposite ends of said water-leg for preventing movement of the products of combustion in a direction parallel to the axis of the 70 75

spiral, said dividing member providing an opening at one point in the spiral path to permit the products of combustion to pass from one side to the other of said member.

5 3. In a boiler construction adapted for the combustion of liquid or gaseous fuels, a boiler head, a water-leg depending therefrom, said water-leg defining a continuous spiral, said water-leg defining a continuous spiral path through which the products 10 of combustion are directed, and a dividing member located in a plane substantially perpendicular to the axis of the spiral and substantially closing the spiral path between the outside of the spiral and the center thereof for preventing movement of the products of combustion along a line parallel to the axis of said spiral, the inner end of said dividing member being spaced from the center of the spiral to provide for movement of said products of combustion from one

10 15

side of said member to the other at the center of said spiral.

4. In a boiler construction adapted for the combustion of liquid or gaseous fuels, a boiler head, a water-leg depending therefrom, said water-leg defining a continuous spiral path through which the products of combustion are directed, a fire box, and means for directing the products of combustion from said fire box through said spiral in planes at right angles to the axis of said spiral, said means including at least one partition positioned in said spiral path at right angles to the axis of the spiral to prevent movement of the products of combustion in a direction parallel to the axis of said spiral, said partition providing 15 an opening at one point in the spiral path to permit the products of combustion to pass from one side to the other of said partition.

PHILIAS P. MONFILS.
